(57) **CLAIM**

The ornamental design for an anti-lost cord for wireless earphone, as shown and described.

DESCRIPTION

FIG. 1 is a front, right and top perspective view of an anti-lost cord for wireless earphone, showing my design. FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

Cords of the anti-lost cord for wireless earphone are shown broken away in the middle to indicate that lengths of the cords are variable.

The broken away symbols form no part of the claimed design.
